UNITED STATES PATENT OFFICE.

GEORGE E. GOUCHER, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,895, dated May 8, 1883.

Application filed February 8, 1883. Term of patent 14 years.

To all whom it may concern:

Be it known that I, GEORGE E. GOUCHER, a citizen of the United States, residing in the city and county of Philadelphia, and State of Pennsylvania, have invented and produced a new and original Design for Fringe, of which the following is a specification, reference being had to the accompanying drawings, forming part thereof.

- 10 Of the drawings, Figure 1 is a front elevation of a fringe embodying my design. Fig. 2 is a cross-section of the pendant.

In the drawings, A are pendants alternately of the form of a hexagonal parallelopipedon and of what I term an "hour-glass spike," which is spirally fluted as to its extremities, but without flutes as to its central portion, ornamented with balls B, and attached to any suitable heading, C.

I claim—

1. A design for fringe, consisting of a heading, and of pendants alternately of the form of a hexagonal parallelopipedon and of an hour-glass spike, substantially as shown and described. 20

2. A design for a fringe, consisting of a heading, and of pendants alternately of the form of a hexagonal parallelopipedon and of an hour-glass spike, and all of which are ornamented with balls, as shown and described. 25

In testimony whereof I have hereunto signed my name this 29th day of January, A.D. 1883. 30

GEORGE E. GOUCHER.

In presence of—

J. BONSALL TAYLOR,
JOHN JOLLEY, Jr.
